UNITED STATES PATENT OFFICE.

JACOB ODELL, OF PETROLEUM CENTRE, PENNSYLVANIA.

IMPROVEMENT IN SUCKER-ROD COUPLING.

Specification forming part of Letters Patent No. **105,235**, dated July 12, 1870.

To all whom it may concern:

Be it known that I, JACOB ODELL, of Petroleum Centre, in the county of Venango and State of Pennsylvania, have invented a new and Improved Sucker-Rod Coupling; and I do hereby declare that the following is a full, clear, and exact description thereof, which will enable others skilled in the art to make and use the same, reference being had to the accompanying drawing, forming part of this specification.

My invention relates to sucker-rod couplings; and consists in an improved construction thereof, as will be more particularly specified hereinafter.

Figure 1 is a sectional elevation of my improved coupling-joint; and Fig. 2 is a transverse section of the same, taken on the line *xx*.

A is the lower section; *B*, the upper one. Both are screw-threaded at the ends, and one has an angular socket in the longitudinal axis, and the other has a corresponding projection, *C*, fitting in the socket, so that one cannot turn independently of the other when coupled together by the internally-threaded thimble or sleeve *D* screwing down from the upper section to the lower one.

At the bottom of the threaded part of the

lower section is a collar, *E*, which prevents the sleeve from working down below the threaded part of the upper section, thereby preventing the joint from working loose.

These sections *A* *B* have deep sockets in the ends for the reception of the wooden rods, which have to be wedged in firmly at the bottom; and in order to insert the wedges readily, I propose to make the wedge-shaped slots *G* through the sides of the sections, through which the wedges may be forced sidewise into the slits in the ends of the wooden sections in a ready and efficient manner.

Having thus described my invention, I claim as new and desire to secure by Letters Patent—

The improved sucker-rod coupling above described, consisting of internally-threaded sleeve *D*, combined with sections *A* *B*, threaded at their ends, one having square projection *C*, and the other a corresponding socket, while the former is provided, also, with wedge-shaped slot *G*, all as and for the purpose described.

JACOB ODELL.
